UNITED STATES PATENT OFFICE.

WILLIAM T. MANN, OF CLEVELAND, OHIO.

FLEXIBLE RAZOR-STROP.

No. 806,419.

Specification of Letters Patent.

Patented Dec. 5, 1905.

Application filed March 28, 1904. Serial No. 200,291.

To all whom it may concern:

Be it known that I, WILLIAM T. MANN, a citizen of the United States, residing at Cleveland, in the county of Cuyahoga and State of Ohio, have invented certain new and useful Improvements in Flexible Razor-Strops; and I do declare that the following is a full, clear, and exact description of the invention, which will enable others skilled in the art to which it appertains to make and use the same.

My invention relates to improvements in flexible razor-strops, all substantially as shown and described, and particularly pointed out in the claim.

15 In the accompanying drawing, forming part hereof, the figure is a perspective view.

The invention as thus shown involves improvement particularly in the strop itself as a medium for sharpening a razor; but in addition to this I employ peculiar means for securing the end of the strop for use. As to the latter feature the construction is such as to prevent the strop from turning or rolling to one side while stropping the razor and which when it occurs subjects the strop to the very common danger of being gashed or cut by accidentally turning the edge of the razor into a cutting relation on the strop. This frequently happens, especially with beginners in the use of flexible strops, because this strop is of the kind which has no backing or stiffening on its back, but is a comparatively thin strip of leather adapted to be used on both sides. Beginners are therefore apt to slash and destroy one or more strops before they can get into the secret of their use, and often the most experienced men will drop into the same accident. This is owing to the swivel or similar rotatable engagement of the strop where it is attached or suspended, and whereby a rolling or turning on the side of the strop is easily induced by excessive pressure of the razor on that side or edge. So far as I know and believe all known flexible swivel-engaged strops are liable to this objection whether they be reversible or not, and it is this lateral rocking movement of the strop that my means of support are intended to obviate; but the essential novelty of this invention is comprised in the character and construction of the strop itself and which has to do in a material sense with the means for engaging the strop. Thus the body B of the strop or the strop itself consists of a piece of suitable leather of medium weight and without backing of any kind on its back and provided at certain advantageous intervals with

rows of holes b transversely, the alternate rows having three and four holes, respectively, of a size relatively as shown and at regular intervals apart as rows. Then between rows there are plain imperforate spaces b', which have been worked out by experiment to get the right width, the idea being that by drawing the razor across the edges of the holes b 60 a peculiar sharpening effect is obtained akin to honing on a suitable smooth stone or other honing-surface, while the intervening space smoothes the edge of the razor. The two actions or effects are obtained at practically 70 the same time and are very marked upon the razor. The holes b are not to be filled with anything whatever, as it is their natural edges upon which I rely to get the effect. If the edge of the razor should get rounded, as is 75 apt to occur especially with flexible strops, the strop can be taken down and laid on a flat surface, with the rougher side of the leather up and the razor passed over the same a few times as needed.

Now referring more particularly to the means for holding the engaged end of the strop it will be seen that the strop is provided with two eyes c in end clip C, one near each edge, which are adapted to engage upon or over two suitable hooks d, fixed into or upon the wall-plate D. Both hooks and eyes are spaced apart alike, and the eyes are engaged directly over the hooks. With this close connection at two points on the wall and at the 90 edges of the strop the pull is evened over the entire surface of the strop and held up firmly at its edges, where all leather strops are inclined to break down and get flabby. Usually I sell wall-plate D with the equipment, 95 and thus all danger of the strop turning under the movements of the razor is avoided. On the contrary, the strop is held practically as straight and flat from edge to edge as a board, and there is no turning in its use.

100 Any suitable handle portion E may be used. In this instance the handle is of leather.

It will be noticed that while the series of holes b are in rows transversely they do not extend to either edge of the strop, but begin 105 inward from the edge, so as to leave an imperforate surface along each edge of the strop across which the razor is necessarily drawn after leaving the said perforations, thus smoothing the blade at the end of each stroke 110 and holding up the edges of the strop. The said perforations also are comparatively infrequent, and the imperforate land or space b between any given row of holes is equal in

width substantially to the greatest length of any one of said rows. This is found by tests and experience to be the better construction. Then, again, the perforations are staggered 5 in alternate rows, and alternate rows also show fewer perforations than the rows next on each side.

What I claim is—

10 A razor-strop comprising a single strap of flexible material provided with a series of rows of unobstructed perforations; the perforations in one row being staggered with re-

lation to the perforations of the adjoining rows, a hand-grip on one end of the flexible strap and a plate carried by the other end of the strap and provided with eyelets located approximately in line with the outer edges of the strap. 15

In testimony whereof I sign this specification in the presence of two witnesses.

WILLIAM T. MANN.
